(57) **CLAIM**

The ornamental design for a shoe, as shown and described.

DESCRIPTION

1. Shoe

- 1.1 is a perspective view of a shoe showing our new design;
- 1.2 is a front view thereof;
- 1.3 is a rear view thereof;
- 1.4 is a side view thereof;
- 1.5 is an opposite side view thereof;
- 1.6 is a top view thereof; and
- 1.7 is a bottom view thereof.

(Continued)

The drawings only show the design on the left shoe; the right shoe is omitted as it is symmetrical to the left shoe.
The evenly dashed lines depict claimed stitching.
